DRESS SHIELDS

Evelyn C. Morris and Beulah Bell-Morris,
New York, N.Y.

Application June 10, 1958, Serial No. 741,109

2 Claims. (Cl. 2—56)

This invention relates to new and useful improvements in dress shields. More particularly, the present invention proposes the construction of an improved dress shield which can easily, quickly and conveniently be removably secured to a brassiere, slip, or the like for underarm use in a dress, blouse or like garment to absorb perspiration, prevent chafing, and protect the garment and under-clothing from perspiration stain.

As a further object, the present invention provides a dress shield for use with strapless dresses and brassieres and for shoulder strap garments of various types.

As a still further object the invention provides a dress shield which is easily laundered and which is provided with an inner moistureproof backing, a cellular plastic foam pad, and an outer cloth layer.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a dress shield embodying the first form of the invention, parts being broken away.

Fig. 2 is an enlarged sectional view taken on line 2—2 of Fig. 1.

Fig. 3 is a sectional view on an enlarged scale taken on line 3—3 of Fig. 1.

Fig. 4 is a sectional view on an enlarged scale taken on line 4—4 of Fig. 1.

Fig. 5 is a perspective view of the dress shield in a folded condition.

Fig. 6 is a view similar to Fig. 1 but showing a modified form of dress shield.

Fig. 7 is a perspective view of a push button clip employed with the dress shield.

Fig. 8 is a side elevational view of the clip in a closed position.

Fig. 9 is a side elevational view of the clip in an open position.

Fig. 10 is a perspective view of the clip in an inverted position.

Referring to the drawings, in the first form of the invention shown in Figs. 1—5 there is shown a dress shield 10 having a generally oval or preferably a rather tapered pear-shaped outline. The shield has a lower, more pointed end 11 and an upper, broader or more rounded end 12. The body of the shield includes a flexible moistureproof backing layer 14. This layer is formed of a vinyl copolymer, polyethylene or plastic sheet material which is highly resistant to salts and acids generally making up perspiration, and which is moistureproof. The second or inner layer 16 is formed of plastic foam material such as polystyrene. This material is chemically inert to body perspiration, just as is layer 14, but the layer 16 is soft and porous and acts like a sponge. This material is superior to sponge rubber because of its greater chemical stability and because it retains its shape

2

longer under hard wear. Also, the plastic foam is more easily cleaned by squeezing in soapy water. The plastic material absorbs perspiration which easily washes out. The foam remains more porous even when highly compacted.

The outer layer 18 is a washable, moisture-absorbing cloth material such as cotton, silk or the like. Synthetic material such as nylon, which does not absorb moisture, is not suitable for the purpose intended.

Plastic layers 14 and 16 may be heat-sealed together as shown by seam 17. The several layers 14, 16, 18 are sewn together at the superimposed peripheries by stitching 20. Disposed between layers 14 and 16 is a wire 22. This wire is formed into a general U-shape and extends around the upper portion 12 and part of the lower portion 11. As shown in Fig. 4, this wire has a core 23 of soft steel, copper, or other untempered metal so that it is readily bent to any desired shape and has moderate shape retaining properties. The core is covered with a plastic sheath 24 made of a thermoplastic material such as a vinyl copolymer. The wire is secured to layer 16 by heat-sealing or by stitching 25. Mounted on the layer 14 is a pair of corrosion-resistant, spaced spring clips 26. Each of these clips, as best shown in Figs. 7—10, has a jaw 28 with teeth 27. The jaw has curled end portions 29 engaged on a pinte 31 carried by the body 30 of the clip. Body 30 is formed of a folded piece of sheet metal to define a generally flat base 32 and an upper rectangular head 34. The base has a plurality of prongs 36 struck outwardly therefrom for engaging layers 14 and 16 when inserted through these layers and folded, as best shown in Fig. 3.

Head 34 has an aperture 38 in which is movably mounted a button 40 having an enlarged base 41 to retain the button in the aperture. The button has a forwardly extending finger 43 disposed to contact a bent finger 42 struck inwardly from jaw 28. Head 34 is formed with curled hinge portions 44 which encircle pinte 31. Between curled hinge portions 44 on pinte 31 is mounted a coil spring 46 having ends disposed to bias the jaw closed with teeth 27 pressed against base 32.

When button 40 is pressed inwardly to the position shown in Fig. 9 the jaw 28 is pivoted open against the tension in spring 46. Release of the button permits the spring to close the jaw.

Small pads 48 may be applied over the folded prongs 36 between layer 16 and 18 as indicated by dotted lines in Fig. 5. These pads may be heat-sealed or stitched to layer 16. If desired, prongs 36 may be cut off from the clips and the clips can be secured to the plastic layer 14 alone by sewing thread. The holes 33 formed in striking out of prongs 36 may serve for attaching the sewing thread. Alternatively, the bases of the clips can be secured to layer 14 by a suitable cement. If the bases 32 are formed of plastic material they can be heat-sealed to layer 14.

Attached to layer 14 are a pair of short spaced elastic bands 54. These bands provide means for securing and engaging the hooks 55 mounted on the opposite ends of strap 56. This elastic strap is adapted to engage the upper arm of the wearer for holding the shield more securely in place if needed. The strap may be removed if not needed.

In use, the dress shield 10 is folded generally along the line A—A indicated in Figs. 1 and 5, with the plastic layer 14 inside and the cloth layer 18 outside. In this folded position the dress shield is disposed under the armpit of the wearer with the cloth side 18 of lower portion 11 against the body. The upper portion 12 may be folded over the top edge of a brassiere or slip and adjusted to any desired position. Then clips 26 may have their jaws 28 engaged on the upper edge of the

brassiere or slip so that the dress shield remains securely in position and does not ride out of place. Strap 56, as mentioned above, provides an additional elastic anchoring means for the shield.

When in use, the folded layer 14 provides a double moistureproof barrier to perspiration. This layer, which is spaced from the outer garment such as a blouse or dress, will not transmit staining perspiration. The doubled plastic foam effectively retains and absorbs the perspiration from arm and body. The cloth layer 18 provides a cool, non-chafing surface against the body and a non-slipping surface against the underarm portion of the blouse or dress. Strap 56 can serve as an independent shoulder strap and need not be engaged with straps of the brassiere or slip worn at the same time. When it is so desired, the shield is readily removed by opening the jaws of the clips. The shield can be squeezed out in soapy water and rinsed by squeezing in clear water and hung up to dry. The entire laundering operation takes but a few seconds.

If desired, the cloth layer 18 and foam layer 16 can be treated by spraying with a suitable antibacterial compound, deodorant, or the like.

In Fig. 6, a modified form of dress shield is shown without the reinforcing wire 22 and without the securing bands 54. In other respects, this form of the invention is similar to the previous form and the various parts may be recognized by corresponding reference numerals with a prime added.

While we have illustrated and described the preferred embodiments of our invention, it is to be understood that we do not limit ourselves to the precise constructions herein disclosed and that various changes and modifications may be made within the scope of the invention as defined in the appended claims.

Having thus described our invention, what we claim

as new, and desire to secure by United States Letters Patent is:

1. A dress shield comprising a generally oval body, said body having a multi-layered structure, a pair of spring clips provided with push button operated pivotable jaws and secured to an outer layer of the body for engaging on portions of underclothing and retaining said body thereon in a folded condition, a pliable shape retaining means disposed between layers of the body said shape retaining means being an untempered metal core covered with a plastic sheath, and a strap removably secured to said body for engaging over the upper arm of the wearer thereof.

2. A dress shield comprising a generally oval body, said body having a multi-layered structure, a pair of spring clips provided with push button operated pivotable jaws and secured to an outer layer of the body for engaging on portions of underclothing and retaining said body thereon in a folded condition, a pliable shape retaining means disposed between layers of the body said shape retaining means being an untempered metal core covered with a plastic sheath, strap retaining means secured to said plastic barrier, a strap removably secured to said strap retaining means, said clips having prongs extending through layers of the body and resilient pads covering said prongs adjacent the body.
